UNITED STATES PATENT OFFICE.

IRVING B. CRANDALL, OF NEW YORK, N. Y., ASSIGNOR TO WESTERN ELECTRIC COMPANY, INCORPORATED, OF NEW YORK, N. Y., A CORPORATION OF NEW YORK.

ACOUSTIC APPARATUS.

Application filed December 24, 1917. Serial No. 208,661.

To all whom it may concern:

Be it known that I, IRVING B. CRANDALL, a citizen of the United States, residing at New York, in the county of New York and **5** State of New York, have invented certain new and useful Improvements in Acoustic Apparatus, of which the following is a full, clear, concise, and exact description.

This invention has reference to improvements in acoustic apparatus for the transmission, reproduction, recording, analyzing and measuring of sound waves. More particularly it relates to telephone transmitters, one of its objects being to produce **10** a transmitter that gives practically a uniform transmission over a greater range of frequency than has heretofore been known.

It has been found that diaphragms such as are used in telephones, phonographs and **20** other acoustic apparatus have a more or less marked natural period for one or more frequencies and if acted upon by waves of these frequencies will respond more than for materially different periodicities. The natural **25** frequency depends in general on the mass, and stiffness of the diaphragm, decreasing with increase in mass but increasing with increase of stiffness.

In the usual telephone diaphragm the lowest natural frequency is in the neighborhood of 1000 cycles per second, which is well **30** within the range of those frequencies used in speech. Because of this natural periodicity and the resulting inequality in response to impulses of different frequencies, a telephone diaphragm will distort speech waves which are impressed on it when the resonance point of the diaphragm falls within that range which is of importance in speech. **35** If, however, the elasticity or the stiffness of the transmitter is increased sufficiently, this resonance point will be removed outside the speech range and there will be a substantial equality of response to all impressed frequencies of the same intensity over a wide range of frequency. This maximum response at the resonance point could also be considerably decreased in value by increasing the damping factor of the vibrating system. The damping factor, in general, depends only upon the frictional forces and upon the inertia, being directly proportional to the frictional forces and inversely proportional to the inertia or mass of the

moving system. Increasing the damping **55** factor therefor gives a vibrating system a frequency characteristic of response more nearly of the ideal form which would be represented by a line parallel to the axis of frequency, indicating thereby an equal response to all frequencies.

Obviously the quality of speech as transmitted by telephonic or phonographic apparatus would be considerably improved by increasing the elasticity and the damping **60** factor of the vibrating system. One way this may be accomplished constitutes the subject-matter of a copending application by E. C. Wente, filed December 20, 1916, Serial No. 137,978, now Patent No. 1,333,744, **65** in which a condenser transmitter is described, which consists of a stretched diaphragm and a stationary member called a back plate in very close face-to-face relation with each other. As described therein, the **70** close adjustment of the two members to each other by virtue of the thin air film so obtained greatly increases the elasticity of the diaphragm and its damping coefficient, so that the natural period peak is removed **75** beyond the upper limit of the frequency range of importance to speech, and reduced to a small value.

It has been found, however, that while such a system offers approximately a uniform response for a wide range, that its response for waves of low frequency depends to some extent upon the frequency. For example, in an instrument in which the back plate was a disc of radius 1.63 cm., and separated from the diaphragm by a distance 0.00022 cm., the response falls in value very rapidly from zero impressed frequency to a frequency of 500 cycles per sec., the response at 500 cycles being less than half that for a **80** constant current voltage of zero frequency. From 500 cycles on to a very high frequency, the response is substantially constant. This distortion at low frequencies is due primarily to the fact that the air between the **85** diaphragm and the adjacent back plate, while escaping freely for low frequency vibrations of the diaphragm, is practically imprisoned for high frequencies, so that the stiffness and damping of the vibrating system is therefore a function of the impressed **90** frequency.

In accordance with this invention, this

distortion at low frequencies is prevented by providing means for allowing this imprisoned air to escape to a definite extent at high frequencies, while still maintaining the close face-to-face relation of the major portions of the two members. That is, this invention provides certain low impedance paths to the outer air for the film of air between the two members that would be otherwise completely imprisoned. As one specific embodiment of this invention, this may be accomplished by providing channels or grooves of suitable depth, width and spacing in the back plate of the vibrating system, in order that the air may escape properly for high-frequency vibrations of the diaphragm as well as for lower frequencies. Obviously, the same result could also be accomplished by inserting apertures suitably spaced and of proper size in the back plate.

It is to be understood that a definite stiffness is obtained from the air film between the sections of the back plate and the diaphragm, and that this stiffness is to be added to the inherent stiffness of the diaphragm, in order to obtain the total stiffness at any given frequency.

It is also to be understood that within certain limits, various combinations of stiffness and damping are added to the system in this invention, the general relation between such added stiffness and damping being that when a maximum effect of stiffness is obtained, a minimum of damping is obtained, and vice versa. Thus, to obtain uniform response over a broad range of frequency, including zero, with a device having a high natural frequency, it is necessary to add both damping and stiffness in definite amounts to the device, by means of the air film between the diaphragm and plate. However it is within the spirit of this invention to so vary the escape of air from the film by the disposition of the grooves or other channels of escape, that all possible combinations of added stiffness and added damping are obtained. For example, as the escape of air is more and more facilitated, the damping effect is made preponderant because the increased air motion allows more work to be done against the frictional forces, while preventing the escape of the air would tend to increase only the stiffness. If it is desired to use a device having its natural frequency peak within the range of importance in speech, it is possible to so apply the grooves to the plate member, and regulate its separation from the diaphragm, that the stiffness and consequently the natural frequency is inappreciably changed, and a maximum of damping is obtained, thereby reducing the peak to a minimum.

This invention will be better understood

by reference to the following detailed description, taken in connection with the accompanying drawings, in which Fig. 1 shows a relation between the amplitude of forced oscillations transmitted, and the frequency of the impressed waves for an air damped transmitter; Fig. 2 is a cross-sectional view of a transmitter of one type that this invention may possess; Fig. 3 is a view in perspective of a portion of Fig. 2; Fig. 4 illustrates this invention in connection with a microphone transmitter; Fig. 5 is a modification that may be made in the structure of Fig. 2; Fig. 6 is a view in plan of a portion of Fig. 5; and Fig. 7 represents an application of this invention to the reproduction or recording of sound waves.

In Fig. 1, curve A is the characteristic curve for a type of a vibrating system in which the stiffness of the vibrating system is much greater for high frequency than for low. The ordinates represent the intensity of response and the abscissæ represent various values of frequency that sound waves may have that are impressed with equal intensity at all frequencies. It is to be noted that the response for zero frequency is large, but that with increase of frequency there is a quick drop to a minimum value, where it remains until the resonance peak begins. This drop in responsiveness, which occurs in the specific instance cited in the neighborhood of 300 to 500 cycles, is caused by the sudden increase in stiffness of the vibrating system, as well as the exceedingly high value of damping at low-frequencies, both of which effects are due to the action of the air between the diaphragm and the plate of the vibrating system. That is, the air between the diaphragm and plate escapes readily for frequencies in the neighborhood of zero cycles, but as the frequency of the vibration of the diaphragm increases, the escape of the air from the film becomes much more difficult, thereby increasing the stiffness of the system and cutting down the intensity of the response until at about 500 cycles, where in the case we are considering, the air seems to be imprisoned practically as much as for considerably higher frequency.

If now, in accordance with this invention, we provide means for allowing the air to escape more readily at high frequencies than for low, the stiffness does not increase so rapidly with frequency, and the decrease in the amount of response, as noted above, would be considerably diminished. A vibrating system of this type properly provided with such a means would therefore have such a characteristic curve of response as that of curve B of Fig. 1.

In Fig. 2 is illustrated a cross-sectional view of one form that this invention may possess, in which the diaphragm 7 and the grooved plate 8 constitute the two members

of the vibrating system. Sound waves incident on the diaphragm cause it to vibrate, thereby causing variations in the thickness of the dielectric in between the plates, and consequently give rise to the variations in the capacity of the condenser. The diaphragm 7 is shown clamped near its outer edges by means of the clamping rings 9 and 10. Ring 12 has in contact with the diaphragm a projection 13 that serves to stretch the diaphragm when suitable compression is inserted between clamping rings 9 and 10, and the ring 12 by means of the bolt 14. The back electrode or plate 8 is fastened to an insulating disc 15 of suitable insulation material, such as bakelite or glass. This disc rests in a recess 16 of the bushing 17, in such a manner that when the rim of the bushing is in contact with the diaphragm near its outer edge, the plate is separated from the diaphragm by a very thin film of air having a thickness of the order from 0.0005 to 0.0020 of an inch. In order to have a uniform air space of such dimensions it is necessary to have the plate and the rim of the bushing very accurately machined and polished. The diaphragm may be stretched by any of the methods known in the art. 18 is a locking ring for the insulating disc 15 and the bushing. 19 is the locking ring for the bushing and the ring 12.

Fig. 3 is a top view of the plate 8 showing how it may be divided by the grooves 20 into a number of sections 22.

Such an arrangement as that of Fig. 2 will have such a characteristic curve as that of curve B of Fig. 1, providing proper values of separation and the size of back plate are selected, since the grooves 20 are so positioned that the film of air between the diaphragm and the various sections may escape to a certain degree even for relatively high frequencies. The size of the sections into which a plate should be divided to obtain the desired result and still preserve a high natural period for the system, depends for a vibrating system of given mass largely upon the distance between the diaphragm and the plate, the smaller the distance between the diaphragm and plate, the smaller should be the area of the sections and the larger the grooves in between. Thus, in one specific illustration with a definite inherent stiffness due to tension in the diaphragm, it was found that the area of each section, in which each section approximated a disc, should be approximately 0.9 sq. cm. In general it may be said that the size of the individual sections of the back plate depends also upon the stiffness per se of the vibrating system, the greater the original stiffness, the larger the area of the sections may be to obtain the substantial equality of response desired.

It is true with practically any size of a disc within reasonable limits that it may

be placed far enough away from the diaphragm in a condenser transmitted that the air can escape to any desired extent from between them and so maintain a fairly uniform response to various frequencies impressed on the diaphragm. However, such an instrument would be less efficient as a transmitter and in addition would possess a higher internal impedance as a condenser, both of which properties are undesirable. In general the size of diaphragm and plate that are used are arbitrary, that is, are fixed by other conditions than the requirement of equal efficiency over a certain range of frequency. And this invention provides a means for modifying such a plate so that the desired frequency characteristics are obtained.

Fig. 4 illustrates this invention in connection with a microphone transmitter of similar structure to that of Fig. 2 with the exception that the back plate 8 has been replaced by back plate 25 in which the central disc contains a carbon chamber 27. The carbon granules 28 are prevented from clogging the space between the diaphragm and the plate by a thin washer 29. The function of this system is similar to that previously described, since the grooves 20 provide ready means for the escape of the air between the disc and the diaphragm for a broad range of frequencies impressed on the diaphragm 7.

Fig. 5 represents a modification that may be made in the back plate of the vibrating system of Fig. 1. In this modification a back plate, 29, is shown having a plurality of apertures 30 employed instead of grooves for providing low impedance paths to the outer air for the escape of the air that would otherwise be imprisoned between the diaphragm and plate. Obviously the grooves in the plate 25 of Fig. 4, may be replaced by apertures in a similar manner.

Fig. 6 is a view in plan of the plate 29 of Fig. 5 and shows a top view of the apertures 30.

Fig. 7 shows how this invention may be adapted to be used as an instrument for recording or measuring sound waves. 40 is a condenser transmitter which may be of the type described which is shown in either Figs. 2 or 4. Connected to one terminal of the condenser is a heated filament 41 of a thermionic amplifier 42. To the other terminal of the condenser is connected the grid element 43 of the amplifier, this amplifier being the usual thermionic amplifier of the audion type now well known in the art. Its output circuit contains the primary transformer winding 45. The secondary winding 46 may be included in a suitable receiving circuit for the amplified electric oscillations from the amplifier which are proportional in intensity and magnitude to the sound

waves impressed on the transmitter. 48 is a battery or other direct source of electro-motive force which is used for polarizing the condenser. In series with source 48 is 5 high resistance 49 which prevents a change of charge on the condenser plates when the diaphragm is vibrating. The input circuit has a source of voltage 50. With such an arrangement, sound waves incident upon the 10 condenser transmitter 40 would produce corresponding electric oscillations in the input circuit of the amplifier 42 which would appear in amplified form in its output circuit 52 where they could be either passed on to 15 another amplifier for further amplification or connected to a system containing a suitable receiving or recording device.

The arrangement of the circuit just described does not form a part of this invention 20 but is described and claimed in a co-pending application of Hartley, Serial No. 53,429, filed September 30, 1915. Although this invention is shown and described as a telephone transmitter, it is to be understood 25 that it may serve equally well as a receiver and although it has been shown in only two modifications, it may be used equally as well in an electromagnetic receiver or transmitter or any other type of receiver or transmitter 30 by such obvious changes as will occur to anyone skilled in the art.

What is claimed is:

1. A device for the transmission of sound composed of two members, a gaseous 35 medium therebetween, said members being in such a close face-to-face relation to each other that the lowest natural frequency of vibration of said device is beyond the range of importance to speech, and means for providing low impedance paths for the gas imprisoned between said members.

2. A device for the transmission of sound composed of two members, a gaseous medium therebetween, said members being in 45 such a close face-to-face relation to each other that the lowest natural frequency of vibration of said device is beyond the range of importance to speech, and means comprising grooves in one of said members 50 whereby low impedance paths are provided for the gas imprisoned between said members.

3. A device for the transmission of sound comprising a diaphragm and a plate, a 55 gaseous medium therebetween, said diaphragm and plate being in such a close face-to-face relation with each other that the lowest natural frequency of said diaphragm is beyond the range of importance to speech, 60 and means comprising grooves in said plate whereby low impedance paths are provided for the gas imprisoned between said plate and said diaphragm.

4. A device for the transmission of sound 65 composed of two members, one of said mem-

bers being a diaphragm and the other being a plate in close face-to-face relation but out of contact with said diaphragm, when said diaphragm is vibrating, said plate being grooved on its face adjacent to said dia- 70 phragm.

5. The device for the transmission of sound comprising two members, one of said members being a diaphragm and the other being a plate in close face-to-face relation 75 but out of contact with said diaphragm, when said diaphragm is vibrating, said plate being divided into a plurality of sections by grooves.

6. A microphone transmitter composed of 80 two members a gaseous medium therebetween, said members being in such close face-to-face relation to each other that the lowest natural frequency of said transmitter is beyond the range of importance in speech, 85 and means for providing low impedance paths for the gas imprisoned between said members.

7. In a microphone transmitter, a vibrating member, and a plate a gaseous medium 90 therebetween, said member and plate being in such a close face-to-face relation that the lowest natural frequency of said diaphragm is beyond the range of importance in speech, 95 said plate containing a chamber for carbon granules, the remainder of said plate being divided into a plurality of sections by grooves.

8. A device for the transmission of sound, composed of two members, a gaseous medium 100 therebetween, said members being in such a close face to face relation to each other that the lowest natural frequency of vibration of said device is beyond the range of importance to speech, and means for allowing the restricted escape of the gas imprisoned between said members while still maintaining said high natural frequency.

9. A telephone device comprising a vibrating member, the normal natural frequency of which is within the range of speech frequency, and means for increasing the natural frequency of said vibrating member above the range of essential speech frequencies and for making said member 115 substantially uniformly responsive to frequencies from zero to the order of 500 cycles per second.

10. A microphone transmitter comprising a vibrating member and a plate, a gaseous medium therebetween, said member and plate being in such close face to face relation to each other that the stiffness of the system for impressed frequencies is increased appreciably by said relation, said plate containing a chamber for granular material, the remainder of said plate being provided with means for allowing the restricted escape of the gas imprisoned between said member and said plate for making 120 125 130

substantially uniform the response of said transmitter for frequencies within the range of importance to speech.

11. A microphone transmitter comprising a diaphragm, and a plate presenting a discontinuous surface to said diaphragm, said diaphragm and said plate being in such close face-to-face relation that the stiffness of the system is increased appreciably by said relation, said transmitter being provided with a chamber for granular material which cooperates with said diaphragm.

12. A microphone transmitter comprising a diaphragm, a plate presenting a discontinuous surface to said diaphragm, said diaphragm and said plate being in such close face-to-face relation that the stiffness of the system is increased appreciably by said relation, and granular material contacting 20 with a portion of said diaphragm.

13. A microphone transmitter comprising a diaphragm, a plate presenting a discontinuous surface to said diaphragm, said diaphragm and said plate being in such close face-to-face relation that the stiffness of the system is increased appreciably by said relation, granular material cooperating with 25 said diaphragm, and means for holding said granular material in its desired position 30 with respect to said diaphragm.

14. A microphone transmitter comprising a vibrating member, a plate having a discontinuous surface in such close face-to-face relation therewith as to appreciably retard 35 the escape of the gas therebetween, said transmitter being provided with a chamber for granular material on the same side of said member as said plate, and means for causing the granular material to contact 40 with only a restricted portion of said vibrating member.

15. A device for the transmission of sound

comprising a diaphragm, and means comprising a plate in close face-to-face relation with said diaphragm for making said diaphragm have a substantially constant response to impressed frequencies of less than 1,000 cycles per second, said plate presenting a discontinuous surface to said diaphragm and said plate being in such close face-to-face relation with said diaphragm that the enclosed film of gas between said diaphragm and said plate escapes readily for low frequencies, but is appreciably retarded by friction for the higher frequencies of importance in speech.

16. A device for the transmission of sound comprising a stretched diaphragm, a plate in close face-to-face relation with said diaphragm, a gaseous medium between said plate and said diaphragm, said plate having discontinuities symmetrically disposed of its face adjacent said diaphragm for allowing the gas enclosed therebetween to escape at such a restricted rate that the device has a substantially constant response for impressed frequencies from zero to 6,000 cycles per second.

17. A device for the transmission of sound comprising a stretched diaphragm, a plate in close face-to-face relation with said diaphragm, a gaseous medium between said diaphragm and said plate, said plate having discontinuities symmetrically arranged with respect to the center of said plate on the side of said plate adjacent said diaphragm for causing said device to have a substantially constant response over a wide range of frequencies of importance in speech.

In witness whereof, I hereunto subscribe my name this 22nd day of December, A. D. 1917.

IRVING B. CRANDALL.
